FIG. 4.

FIG. 2.

FIG. 3.

FIG. 1.

FIG. 5.

FIG. 6.

FIG. 1 is a side elevational view of a combined camera and case therefor or similar article, showing my new design, the opposite side being substantially a mirror image thereof;

FIG. 2 is an exploded front elevational view;

FIG. 3 is an exploded rear elevational view;

FIG. 4 is a top plan view;

FIG. 5 is a bottom plan view of the case alone; and

FIG. 6 is a top plan view of the lower portion from the plane 6—6 in FIG. 2, the upper portion being omitted for convenience in illustration.

The actuating cord projecting from the bottom in FIG. 2 has been omitted from FIGS. 1 and 3 for convenience in illustration.

I claim:

The ornamental design for a combined camera and case therefor or similar article, substantially as shown and described.
